UNITED STATES PATENT OFFICE.

GEORGE W. NEVILL, OF RICHMOND, VIRGINIA.

IMPROVEMENT IN DITCHING-MACHINES.

Specification forming part of Letters Patent No. 123,286, dated January 30, 1872.

Specification describing a new and Improved Ditching-Machine, invented by GEORGE W. NEVILL, of Richmond, in the county of Henrico and State of Virginia.

The invention will be first fully described and then clearly pointed out in the claim.

Figure 1 is a central longitudinal section of the machine. Fig. 2 is an elevation of the right side of wheel and discharge-spout. Fig. 3 is a longitudinal section of one of the friction-rolls of endless carrier. Fig. 4 is a detail view of side cutters. Fig. 5 is a section of carrier-wheel, showing the divergence of flanges. Fig. 6 is a detail view of spout. Fig. 7 is a plan view of stock for side-cutters and guide.

A¹ is a frame, and A² a bar diverging rearwardly to press the dirt from the ditch after it falls from the spout. A is a cast-iron wheel provided with slightly-flaring vertical flanges a a. a' a' are straps, in which the wheel has its bearings, and which are pendent from a frame, B. This frame B is itself pendent from a cross-bar, b, which rests upon uprights b¹ b¹ by means of hook and eye b² b³, when the ditcher is not at work, and is attached thereto by means of windlass b⁴ and rope b⁵ when in full operation. In the rear of frame B is located the broad endless carrier C, which works upon pulleys c c pivoted at the ends of a small frame whose sides c¹ form lateral guides to the dirt. These are formed of a shaft provided with three disks, c², so that when the dirt presses upon the belt the end disks will allow a longitudinal cavity to receive it, while the middle one will prevent the belt from being drawn in too much at the center of the pulley. D is a stationary scraper-spout, having one end, d, to act as the scraper, and the other, d², to serve as the discharge-spout. From the part d to the middle of curve d¹ there is an upward incline, and from that point to the end of spout a gradual decline. This acts upon the dirt somewhat in the same manner as the mold-board of a plow. E E are knives to loosen the sides of the packed dirt just previous to its delivery upon the scraper d. These knives are placed at top of wheel, on opposite sides, and one in advance of the other. The object of placing them one before the other is that they may not press the dirt at opposite points and pack it too much, as well as cause unnecessary fric-

tion. E' E' are scrapers to act upon the side of wheel. F is the cutter, corresponding in width with the distance between flanges a a, and having two cutting-edges, f f, which form the sides of an isosceles triangle. This gives a shearing cut on each side of the vertex of the angle or middle of the furrow-slice. G G are two lateral cutters, whose points are in the same line with the flanges a a, but the cutters diverge slightly but gradually upward. They are set on each side of the machine, and one in advance of the other. The purpose of this construction is to afford lateral play to the wheel in its subsequent travel when it successively deepens the ditch. The lower part of these knives cut a portion of earth equal to depth of the wheel-flanges, while the upper part pares off the previous cut a little more to allow the wheel and its frame to be let down easily and without sticking between the sides of the ditch. These cutters are set one in front of the other, so as not to compress the furrow-slice between them and to avoid friction. H is a friction-roll, which rests upon the top of the furrow-slice which is about to be removed. H' is a cast frame, which is constructed to act as a holder for the lateral cutters and regulating-roller, and also as a guide. This frame is bifurcated in front for the purpose of receiving wheel H, is of about the same width as distance between flanges of wheel A, and is attached to the lower front end of pendent sliding-frame B. The sides of this frame are bulged out so as to be a distance transversely across equal with that of the wheel. This serves as a guide to keep the wheel directly in line of cut after the first slice is taken out. I is the upper tongue, pivoted to the lower, while the latter is pivoted between hounds K K. This allows the tongue which carries the guide L and guide-wheel to gradually sink lower and lower in the ditch until the work is completed. L is a guide, which does not touch the furrow-slice at any time, but after the first cut is made moves between the concavity formed, and serves to keep the horses in proper line on each side of the excavation. M is a lever and N a cord attached to the lower tongue to enable them to be elevated, if desired.

The machine being transported to the intended scene of operation, the wheel A is

dropped and allowed to rest with its weight upon the ground. The horses being started, the lateral cutters G G cut vertically into the ground. The angular horizontal steel-plate F cuts out the bottom and raises the loosened slice. This is pressed backward by its own mass in front until it reaches the endless carrier. This carrier, being made taut by friction, revolves upon its rolls and sustains the weight of the moving mass nearly without friction, because it moves with said mass. The soil, after reaching nearly to a horizontal position on the top of wheel, is carried forward, loosened, and unpacked on the sides by knives E E. It is then discharged on the scraper d, up the mold-board incline d¹, whence it is discharged from the spout d². After one furrow-slice is cut the operation is successively repeated until the requisite depth is obtained. After the first cut the guide L subserves the very important use of helping to maintain all parts of the machine in their true relation to the line of travel. This guide is rigidly attached to tongue, and gradually increasing in width from front to rear.

I am aware that friction-rolls have been used for this purpose, but as they act by rolling friction the dirt gathers and becomes packed on their peripheries. Hence, in order to enable them to work advantageously they require cleaner attachments, which are in the way.

Having thus described all that is necessary

to a full understanding of my invention, what I esteem to be new, and desire to protect by Letters Patent, is—

1. The combination, in a ditching-machine, of a flanged revolving carrier-wheel, A, with the two lateral cutters G G set upon opposite sides, one in advance of the other, and both constructed as and for the purpose described.

2. The separating-knives E arranged on opposite sides and near the top of flanged wheel A, one in front of the other, and both in rear of scraper d, as and for the purpose described.

3. The scraper-spout D having bottom scraper d, upward incline d¹, and spout d², constructed and applied as and for the purpose set forth.

4. The cast frame H', when constructed as described, so as to adapt it to serve as cutter-stock, regulating wheel-stock, and wheel-frame guide, as set forth.

5. The upper and lower tongue combined, as described, with hounds, so as to allow the lower tongue, which carries the furrow-wheel and guide L, to gradually go lower as the ditch becomes deeper.

The above specification of my invention signed by me this 23d day of November, A. D. 1871.

G. W. NEVILL.
